ELECTRICALLY HEATED STEAM IRON

Edward J. Wiggins, Chicago, Ill., assignor to Jack Galter, Chicago, Ill.

Application December 13, 1939, Serial No. 308,893

3 Claims. (Cl. 38—77)

This invention relates to an electrically heated steam iron for use in ironing clothes, pressing washed goods and for other similar purposes.

One of the problems of previous irons of this type is the passage of water by condensation of steam or otherwise onto the fabrics being ironed or pressed so as to spot the same, or cause other inconvenience, destruction or annoyance.

It is among the objects of this invention to provide a construction that will solve this problem and prevent the exit of any water by condensation of steam or slopping from the iron. Another object is to provide a simple yet accurate means for indicating from the exterior of the iron the level of the water contained therein, so as to prevent unexpected scorching from a dry iron. My invention also contemplates such other objects, advantages and capabilities as will later more fully appear and which are inherently possessed by my invention.

While I have shown in the accompanying drawings a preferred form of my invention, yet I wish it understood that the same is susceptible of modification and change without departing from the spirit of my invention.

Referring to the drawings, Fig. 1 is a sectional view of my steam iron; Fig. 2 is a rear elevational view; Fig. 3 is a top plan view with the handle plate removed; Fig. 4 is a bottom plan view showing the heating element; Fig. 5 is a top plan view of the shoe plate; Fig. 6 is a sectional view on line 6—6 of Fig. 1; Fig. 7 is a sectional view on line 7—7 of Fig. 1; Fig. 8 is a sectional view on line 8—8 of Fig. 1; Fig. 9 is an enlarged detail sectional view of the lower front portion of the iron; Fig. 10 is a detail sectional view of a modified form of discharge openings, and Fig. 11 is a detail view of the flap valve baffle member.

The embodiment selected to illustrate my invention comprises a shoe plate 10 having a smooth outer bottom ironing or pressing surface 11 and a body member 12 attached to said shoe plate 10 by suitable means such as screws 13. The bottom of the body member 12 has a slight depression 14 to which is attached an electrical element 15. A corresponding depression 16 is also provided in the inner and upper portion of the shoe plate 10 to accommodate the electrical element 15 when the body member 12 is attached to the shoe plate 10.

The body member 12 is hollow so as to provide a water chamber 17. At the upper front portion of the interior of the body member 12 is a steam chamber 18 extending from about the middle upper portion of the body member 12 forwardly un-

der the dome portion 19. The rear wall 20 of the steam chamber 18 has an opening 21 to receive steam rising from the water chamber 17.

The outer top 22 of the body member 12 has a recess 23 with an indented flange 24 to receive the handle plate 25. Screws 26 attach the handle plate 25 to the flange 24. A handle 27 is attached to the handle plate 25.

Adjacent the upper ends of rear wall 20 of steam chamber 18 is swingably attached a flap valve or baffle member 28 by extensions 29 in openings 30 in the inner side walls of the flange 24. The baffle member 28 has a closed upper portion 31 and integral therewith a pair of legs 32 spaced by cut-out portion 33. Baffle member 28 is so positioned that it does not normally cover opening 21 in the rear wall of steam chamber 18, thereby permitting steam to freely enter opening 21 and pass from water chamber 17 to steam chamber 18. When however the iron is moved forwardly, as it is in use, baffle member 28 receives pressure from the water in the iron and swings forwardly to temporarily or momentarily close opening 21 to prevent the accidental slopping of water from the water chamber 17 into steam chamber 18. This is one of the features designed by me to block the passage of water so as to prevent any undesired exit of water from the iron on the object being pressed.

The steam chamber 18 is adapted to hold a filter 34 of copper mesh or the like, which rests on floor 35. The filter 34 also acts to condense, and water therefrom will drop back into water chamber 17 through aperture 36 in floor 35 of the steam chamber 18.

It will be noted that steam chamber 18 continues under dome portion 19, where the steam passes up into the top opening of a spiral steam receiving pipe 37 which passes spirally downwardly through an opening 38 in the front bottom portion of the body member 12. The steam strikes a hot spot and water vaporizing guide 39 in the front inner surface of the shoe plate 10 and is directed to rounded depression therein to pass out through a plurality of discharge openings 40.

In use, it will be noted that water is prevented from entering the steam chamber 18 by means of the flap valve baffle member 28. Condensation by means of the filter 34 prevents cooling steam from entering the steam receiving pipe 37. The inner walls of the dome, and the centrifugal passage of the steam in the heated walls of the spiral steam pipe 37 superheat the steam to prevent condensation. As a final safeguard the hot

spot guide 39 acts to again superheat the steam to guarantee that no water will pass out the discharge openings 40.

Attached to the bottom of the handle plate 25 5 is a cradle 41 having a bar 42 rotatably attached thereto. Attached to said bar 42 is a rod 50 having on its inner end a non-absorbable float 43 and on its outer end an indicator 44. The float 43 extends into the water chamber 17 10 through recess 23 and floats on the water in the space 33 between legs 32 of baffle member 28. The indicator 44 is visible through window 46 in the handle plate 25 so that the level of the water may be determined from the exterior of the iron. 15 In this way there is no need to iron until the iron is dry—the objects ironed being scorched and the iron impaired. The indicator, easily and readily seen, warns the user in advance of trouble.

An opening 47 is provided in the top of the body 20 portion 12 within which water may be poured for the water chamber 17. This opening is protected by a removable thumb nut type of screw 48.

At the rear of the iron, electrical plugs 49 communicating with the electrical element 15 in 25 the iron are provided for contact with an electrical source of supply.

I may provide my steam discharge openings 40 with a Venturi nozzle construction as shown in Fig. 10. It will be noted that the spaced entrance 30 walls 51 are inclined inwardly toward each other at a 30 degree angle. The spaced exit walls 52 continue from the outer ends of the entrance walls 51 and are inclined outwardly at a 15 degree angle which is exactly half the degree of incline 35 of the entrance walls. The entrance walls extend for one-third of the length and the exit walls for two-thirds of the length of the discharge openings 40. The steam passing through the narrowed opening 53 formed by the walls 51 and 40 52 at the meeting point has the speed and volume of its flow increased so as to perform a more efficient operation.

Having thus described my invention, I claim:

1. An electrically heated steam iron comprising 45 a shoe plate having an outer ironing surface and steam discharge openings, a hollow body member attached to said shoe plate, an electrical element having means for connection with an electrical source of supply, said electrical element positioned between said shoe plate and said body member, said body member having a water chamber and means for the reception of water for 50 said water chamber, a steam chamber formed within said hollow body member above the water

chamber, said steam chamber having an opening to receive steam formed in the water chamber, a flap valve member swingably positioned adjacent said opening in the steam chamber and adapted to normally permit entry of steam in 5 said opening, said flap valve member adapted upon forward movement of the iron to receive pressure from water in the iron as it rebounds against said valve and to swing to close said opening so as to prevent the passage of water therein, a steam conduit with its upper end in the steam chamber and its lower end communicating with said steam discharge openings in the shoe plate, and a handle attached to said body member.

2. In an electrically heated steam iron, a body 15 member having a hollow interior providing space for a water chamber, a steam chamber positioned in said hollow interior of the body member above the water chamber, said steam chamber having an opening to receive steam formed in the water 20 chamber, a flap valve member swingably positioned adjacent said opening in the steam chamber and adapted to normally permit entry of steam in said opening, said flap valve member adapted upon forward movement of the iron to receive pressure from water in the iron as it rebounds against said valve and to swing to close said opening so as to prevent the passage of water 25 therein.

3. An electrically heated steam iron comprising 30 a bottom shoe plate having an outer ironing surface and a plurality of steam discharge openings, a body member attached to said shoe plate, an electrical element having means for connection with an electrical source of supply, said electrical element positioned between said shoe plate and said body member, said body member having a hollow interior and a dome-shaped upper portion, the lower portion of the hollow interior of 35 said body member forming a water chamber, means in said body member for the reception of water for the water chamber, a steam chamber positioned above said water chamber and having an opening to receive steam formed in said water chamber, a steam delivery tube with its upper end in the steam chamber, said steam delivery tube having means for imparting a spiral movement to the steam passing therethrough, whereby the heavy condensate is thrown radially outward into contact with the hot tube walls, the lower end of said steam delivery tube communicating with said steam discharge openings in the shoe plate and a handle attached to said body member.

EDWARD J. WIGGINS.
